ACETYLENE GENERATOR

Elmer H. Smith, Minneapolis, Minn., assignor to
 Smith Welding Equipment Corporation, Minneapolis, Minn., a corporation of Minnesota

Application February 27, 1939, Serial No. 258,769

7 Claims. (Cl. 48—53.3)

This invention relates to new and useful improvements in generators, and more particularly to the means for feeding or precipitating the carbide into the water in the generator.

Acetylene generators, as is well known, comprise a carbide hopper having a discharge opening in its lower portion through which the carbide is fed to the gas generating chamber. The carbide being of granular consistency, or in the form of small lumps or particles, has a tendency to bridge over the discharge opening of the hopper and cause uneven feeding thereof, when the valve which normally closes said opening is open. Such bridging of the carbide over the discharge opening of the hopper may be prevented by agitating the valve so as to dislodge the carbide particles tending to bridge over the discharge opening.

Numerous mechanisms have heretofore been devised to agitate or relatively move the valve with respect to the discharge opening, to prevent such bridging of the carbide. Some of these mechanisms have been more or less practical in operation, but have not been positive in operation. Others have been too expensive in construction.

The novel valve-agitating means herein disclosed, has proven very practical and positive in operation. Its operation is controlled by the flow of gas from the gas generating chamber to the gas storage chamber of the generator, whereby when gas is passing from the gas generating chamber to the gas storage chamber, said device is actuated to cause the valve to be agitated whereby it will dislodge any particles of carbide tending to bridge over the discharge opening of the hopper bottom.

An important feature of the present invention resides in the construction of a novel carbide feeding mechanism comprising a rotary member for imparting relative movement to the carbide control valve, and which rotary member is actuated by the passage of the gas from the gas generating chamber to the gas storage chamber.

A further object is to provide a generator comprising a casing adapted to contain water and having an inner casing member secured to and suspended from the upper wall thereof and spaced from the main casing wall to provide an annular chamber between said inner and outer casing members, and a carbide hopper being mounted on the upper wall of the generator in communication with the gas generating chamber defined by the inner casing member, said hopper having a valve for controlling the feeding of carbide from

the hopper to the gas generating chamber, and a rotary member being mounted within the generator and having a plurality of pockets in its periphery adapted to receive gas passing from the gas generating chamber to the storage chamber, whereby the gas will impart rotary movement to said member and thereby agitate the carbide control valve, which is operatively connected to said member.

A further object is to provide a generator comprising a gas generating chamber and a gas storage chamber, and a carbide hopper having a discharge opening, and a valve for controlling the flow of carbide through said opening to the gas generating chamber, and a rotary member, having a plurality of pockets in its periphery, being so mounted that the gas flowing from the gas generating chamber is received in the pockets of said rotary member at one side of its center, whereby the buoyancy of the gas will impart rotary movement to said member, and said member being adapted to operate a rod having a connection with the carbide control valve, whereby when the rotary member is rotated, said rod will agitate the valve, thereby preventing the carbide from bridging over the discharge opening of the hopper, when the valve is open.

Other objects of the invention reside in the novel construction of the valve agitating means, the operation of which is controlled entirely by the flow of gas from the gas generating chamber to the gas storage chamber; in the novel construction of the connecting means between the carbide control valve and the rotary member; in the construction and mounting of the rotary member, which is such that said member will require no attention on the part of the operator, and whereby it is positive in operation, and will impart sufficient movement to the carbide control valve to positively prevent bridging of the carbide in the discharge opening of the hopper, thereby to provide a more uniform flow of the carbide from the gas generating chamber to the storage chamber, when the control valve is open; and, in the construction of such a generator wherein the carbide hopper, including the carbide feed valve and the means for controlling said valve, may be removed from the generator as a unit.

Other objects of the invention will appear from the following description and accompanying drawings and will be pointed out in the annexed claims.

In the accompanying drawings there has been disclosed a structure designed to carry out the various objects of the invention, but it is to be

understood that the invention is not confined to the exact features shown as various changes may be made within the scope of the claims which follow.

In the drawings:

Figure 1 is a vertical sectional view of a generator, showing the invention embodied therein;

Figure 2 is an enlarged detail sectional view on the line 2—2 of Figure 1, showing the preferred construction of the rotary valve-agitating member;

Figure 3 is a sectional plan view on the line 3—3 of Figure 2;

Figure 4 is an enlarged detail sectional view showing the carbide control valve in open position; and

Figure 5 is a view similar to Figure 4, with some of the parts omitted, and showing the valve in closed position.

In the selected embodiment of the invention here shown, there is illustrated for purposes of disclosure, an acetylene generator comprising a casing 2 having a bottom wall 3 and top wall 4. The casing 2 is adapted to contain a quantity of water, as is customary in carbide generators.

An inner casing or wall member 5 is shown secured to the top wall 4 of the generator and depends therefrom with its wall spaced inwardly from the outer casing wall 3 to provide an annular space or chamber 6, the bottom of which is defined by the water lever 7. To simplify the description of the apparatus, the annular space 6 will hereinafter be referred to as the gas storage or receiving chamber 6, and the chamber within the wall member 5, as the gas generating chamber 8. The bottom of the latter chamber is defined by the water level 9.

A carbide hopper, generally indicated by the numeral 11, is provided on top of the generator, and has a hopper bottom 12 provided with a discharge opening 13. The hopper discharge opening 13 communicates with the gas generating chamber 8 through a tubular member 14, shown mounted within a relatively larger tubular member 15, received in an opening 16 provided in the top wall 4 of the generator. The tubular members 14 and 15 are secured together in spaced relation by a suitable plate 17, which preferably is welded to said members. The upper end of the inner member 14 is preferably suitably secured to a ring-like member 18, by such means as welding, which member has oppositely disposed lugs 19 adapted for interlocking engagement with lugs 21 provided on a hopper base 22, secured to the bottom of the hopper, as shown at 23. The ring-like member 18 forms the hopper discharge opening 13. The hopper base is provided with radial arms 25 adapted to be engaged with studs 26, thereby to secure the hopper in position on the top wall 4 of the generator. A suitable rubber gasket 27 is supported on a seat 28 formed on the top wall 4 of the generator, and the upper portion of the gasket 27 is adapted to be engaged by an annular flange 29 of the hopper base 22, whereby the hopper may be secured to the top wall 4 of the generator in leak-proof relation.

A suitable valve 31 is shown secured to the upper end of a tubular member or sleeve 32, having its lower end outwardly flared, as shown at 33. The lower end of a rod 34 is received in the upper end of the sleeve 32, and said rod passes through an opening 35 provided in the

valve 31. A suitable coiled spring 36 is coiled about the rod 34 within the sleeve 32 and has one end seated against the bottom face of the valve 31, and its opposite end against a head 37 provided on the lower end of the rod 34. A pin 38 is secured in the wall of the sleeve 32 to limit downward movement of the rod 34 within the sleeve 32. The largest diameter of the valve 31 is slightly less than the opening of the valve 13 in the member 18, whereby the valve 31 may pass into the discharge opening 13, as will be readily understood by reference to Figure 5.

The upper end of the rod 34 has a ball 41 secured thereto, which is supported within a recess 42 provided in a head 43 secured to a diaphragm 44. A nut 45 is received in threaded engagement with the head 43 to inseparably secure the rod 34 to said head. The diaphragm is shown having its marginal edge clamped between the upper horizontal edge portion of the carbide hopper 11 and a hood 39, by suitable bolts 46. A compression spring 47 is mounted within the hood 39 and has its lower end bearing against a suitable washer or plate 48, seated against the upper surface of the diaphragm 44. The upper end of the spring 47 engages the bottom of a recess 49 provided in a cup-shaped member 51, received in threaded engagement with the upper end of the hood 39.

The head 43 has a stem 52, the upper end of which is received in a socket provided in the lower end of a stud 53. The stud 53 has a threaded socket 54 at its upper end adapted to receive the threaded terminal 55 of an adjusting wheel 56, having a hub received in a suitable counterbore 57 provided in the nut 51. The adjusting wheel 56 provides means whereby the valve 31 may be moved into closed position, as shown in Figure 5, to prevent feeding of the carbide from the hopper 11.

An important feature of the present invention resides in the novel means provided for agitating the valve 31 to provide a more uniform flow of carbide from the hopper 11 through the discharge opening 13 to the gas generating chamber 8.

The means provided for thus agitating the valve 31 comprises a rod 58, the upper end of which is shown received in the lower flared end of the tubular member 32 of the valve, as best shown in Figures 4 and 5. The lower end of the rod 58 is secured to a rock shaft 59, shown supported in suitable hangers 61 and 62 secured to the inner casing member 5. Suitable collars 63 are secured to the shaft 59 to prevent axial movement thereof.

One end of the rock shaft 59 is shown provided with an upstanding arm 64 having a head 65 provided with inwardly directed terminals 66, which cooperate with a star wheel 66 to provide an escapement, as best shown in Figure 2. The star wheel 66 is secured to a shaft 67 of a suitable rotor, generally indicated by the numeral 68. The shaft 67 has one end supported in a bearing provided in the offset wall portion 69 of the inner casing member 5, and its opposite end in the lower end of a hanger 71, secured to the upper portion of the casing 5. A suitable brace 72 has its end portions suitably secured to the wall of the casing 5, as shown at 73 in Figure 2, and its intermediate portion is secured to the hanger 71, as shown at 74 in Figure 2.

The rotor 68 has a plurality of pockets 75 in its periphery adapted to receive gas from a small inverted V-shaped duct 76 secured to the lower

edge of the wall of the member 5. When the pressure of the gas in the generating chamber 8 forces the level of the water downwardly to a point below the uppermost portion of the V-shaped duct 76, gas will flow from the gas generating chamber 8 through the duct 76 and into one of the pockets of the rotor, as shown in Figures 1 and 2. The buoyancy of the gas, when thus entering the pockets in the rotor to one side of the center of the shaft 67, will impart a rotary movement to the rotor in the direction indicated by the arrow in Figure 2. Such rotary movement of the rotor will impart a similar motion to the star wheel 66, whereupon the terminals 60 of the arms of the head 65 will follow the contour of the teeth of the star wheel, as in an ordinary escapement, and thereby impart an oscillatory movement to the upstanding arm 64 of the rock shaft 59. Such oscillatory movement of the arm 64 will impart a similar movement to the rod 58, which, because of its upper end being received in the lower end of the tubular member 32 of the valve, will agitate the valve 31 to cause the carbide to feed more uniformly from the carbide hopper into the gas generating chamber 8. Such agitation of the valve 31 will also prevent the carbide from bridging over the discharge opening 13 of the hopper.

To operate the apparatus, the carbide hopper is removed from the generator by loosening the nuts of the studs 26, whereby the hopper, including the tubular members 14 and 15, may be removed as a unit from the generator. The tubular members 14 and 15 are then removed from the hopper base 32 in the usual manner, and after the hopper is filled with carbide, the tubular members 14 and 15 are replaced in the hopper base, and the entire hopper may then be secured to the top of the generator, as shown in Figure 1.

When the carbide hopper has thus been replaced on the generator, the hand wheel 56 is rotated in a direction to cause the spring 49 to force the diaphragm 44 downwardly to substantially the position shown in Figure 1, wherein the valve 31 is moved downwardly to open position, as shown in Figure 4. As the carbide is precipitated into the water in the gas chamber 8, gas is generated and rises into said chamber and eventually forces the water level therein downwardly to substantially the level shown at 9 in Figure 1, whereby the gas in the chamber 8 will escape therefrom into the pockets of the rotor and upwardly into the gas storage chamber 6. As the gas enters the pockets of the rotor 68, the buoyancy thereof will impart rotary movement to the rotor, whereby the valve 31 is agitated because of its connection with the rotor through the arm 64, shaft 59, and rod 58.

When the pressure in the gas generating chamber 8 reaches a predetermined figure, the diaphragm 44 is forced upwardly against the tension of the spring 47, thereby closing the valve 31 and interrupting further flow of carbide from the hopper into the gas generating chamber. It is to be understood that the gas pressure in the hopper is equal to the pressure in the gas generating chamber 8, because the hopper is in direct communication with the gas generating chamber through the spaces between the carbide particles in the hopper 11.

When feeding of carbide into the gas generating chamber is interrupted, as above stated, the rotor 68 may cease to rotate, because the level of the water in the gas generating chamber 8 may then rise above the V-shaped duct 76, and

thereby shut off the flow of gas from the chamber 8 to the gas storage chamber 6. As gas is drawn from the gas storage chamber 6 through the service line or take-off 77, shown in Figure 5, the pressure in the gas storage chamber 6 decreases, whereby gas may again be forced from the chamber 8 into the chamber 6 through the duct 76. Such flow of gas from the chamber 8 to the chamber 6 will release the pressure in the chamber 8, whereby the spring 47 will force the diaphragm 44 downwardly to open the valve 31. At substantially the same time, the rotor 68 may commence to rotate because of gas entering the pockets 15 thereof, from the duct 76, as shown in Figure 2, whereby the valve 31 is agitated to provide a uniform flow of carbide from the hopper 11 to the gas generating chamber. It will thus be seen that the operation of the apparatus is entirely automatic and when no gas is being drawn from the service line or gas take-off 77, the valve 31 may eventually close, whereby all movable parts will come to rest, in which condition they will remain until gas is again drawn from the service line 77.

In an ordinary generator, the space between the carbide feeding means or control valve 31, as shown in Figure 1, and the water level 9, is usually about 10 inches, which is the minimum requirement by the Underwriter's Laboratories. If this distance is increased, the gas storage space between the carbide feed valve is correspondingly increased. This is objectionable, because when the generator is initially charged with water, some air is entrained with the water, and when the capacity of the chamber 8 between the carbide feed valve and the water level 7, is relatively large, a longer time is required to clean or purge said chamber of the air entrained with the water. On the other hand, the distance between the carbide feed valve and the water level 9 should be sufficient to prevent the water from splashing against the parts of the feed valve, when the carbide strikes the surface of the water in the bottom of the chamber 8.

I accomplish this desirable feature in the structure herein disclosed because of the novel construction and arrangement of the parts of the apparatus. By reference to Figure 1, it will be noted that when the generator is initially started, carbide is precipitated into the water in the chamber 8, whereby gas is immediately generated in said chamber. The pressure of the gas thus generated, forces the water level 9 downwardly until it reaches substantially the level shown in Figure 1, after which the gas will escape from chamber 8 into the annular space or chamber 6, through the duct 76.

The means provided for agitating the carbide control valve 31 is very simple in construction and has been found very efficient in practical operation. The agitation of the valve 31 is controlled entirely by the flow of gas from the gas generating chamber 8 to the gas storage chamber 6, through the duct 76.

The length of the rod 58 is such that when the sleeve 32 of the valve 31 is in its uppermost position, as when the valve 31 is closed, as shown in Figure 5, the lower flared end of the tube 32 will be so positioned with respect to the upper end 70 of the rod 58, that the rod may oscillate without imparting lateral movement to the valve 31, as shown by the dotted lines in Figure 5. The lower flared end of the sleeve 32 facilitates mounting the carbide hopper upon the generator in that it guides the upper end of the rod 58

into the sleeve 32, as will readily be understood by reference to Figures 4 and 5. Generators of this general type are sometimes provided with agitating means in the lower portion thereof, but as this mechanism forms no part of the present invention, it has been omitted from the drawings.

I claim as my invention:

1. In a generator of the class described, a casing having water therein, a wall member within said casing and spaced from the casing wall and having an open end sealed by the water in the generator, said inner wall member defining a gas generating chamber and cooperating with the wall of the casing to provide a gas storage chamber which surrounds the gas generating chamber, a carbide hopper having a discharge opening communicating with the gas generating chamber, a valve for controlling the flow of carbide through said opening, a rock shaft within the generator, a rod secured to said shaft and engaged with the valve, a rotor, an escapement connecting the rotor to the rock shaft, and a duct in the lower portion of the gas generating chamber through which the gas must pass from the generating chamber to the storage chamber, the gas flowing through said duct being received in pockets provided in the periphery of the rotor, whereby the rotor is rotated to actuate the escapement and rock said shaft and thereby cause the rod to agitate the valve, when the latter is open.

2. In a generator of the class described, a casing comprising an upper wall and having water in the lower portion thereof, a wall member secured to and depending from said upper wall and spaced from the casing wall, said inner wall member defining a gas generating chamber and cooperating with the casing wall to provide a gas storage chamber which surrounds the gas generating chamber, the level of the water in said chambers defining the bottoms thereof, a carbide hopper having a discharge opening communicating with the gas generating chamber, a valve for said opening, a duct in the lower portion of the inner wall member for conducting gas from the generating chamber to the storage chamber, and means for agitating the valve, when the valve is open and gas is flowing from the generating chamber to the storage chamber, said valve-agitating means comprising an escapement having an operative connection with the valve, and a rotor having pockets in its periphery adapted to receive the gas flowing from the generating chamber to the storage chamber, whereby the rotor is rotated to actuate the escapement which, in turn, effects a lateral movement to the valve to prevent bridging of the carbide in the discharge opening of the hopper, when the valve is open.

3. In a generator of the class described, a casing having wall means therein defining a gas generating chamber and cooperating with the casing wall to provide a gas storage chamber, the bottoms of said chambers being defined by the levels of the water in the respective chambers, a carbide hopper having a discharge opening communicating with the gas generating chamber, a valve for controlling the flow of carbide through said opening, a tubular member secured to and depending from the valve, a duct for conducting gas from the generating chamber to the storage chamber, and means for agitating the valve, when the valve is open and gas is flowing from the generating chamber to the storage

chamber, said means comprising an escapement having a rod received in the lower end of the tubular valve member, and a rotor for operating said escapement, said rotor being mounted between said wall means and the casing wall and adapted to be rotated by the flow of gas from the generating chamber to the storage chamber.

4. In an acetylene generator, a casing having a water chamber therein, a carbide hopper having a discharge opening in communication with the water chamber, a pressure-operated valve for controlling the flow of carbide through said discharge opening, and means for agitating said valve comprising a gas-operated rotor having an escapement mechanism operatively connecting it to said valve, whereby when said gas is flowing from the generator, said valve is agitated to provide a more uniform flow of carbide from the hopper to the water chamber.

5. In an acetylene generator, a casing having water therein, means within the casing defining a gas generating chamber and a gas storage chamber, the bottoms of said chambers being sealed by said water, a carbide hopper in communication with the gas generating chamber and having a discharge opening, a valve for controlling the flow of carbide through said opening, means responsive to variations in the pressure in the generating chamber to control the operation of the valve, a duct for conducting gas from the generating chamber to the storage chamber, and means for agitating the valve to prevent bridging of the carbide in the discharge opening of the hopper, when the valve is open, said valve-agitating means including a rotor having pockets in its periphery arranged to receive the gas flowing from the generating chamber to the storage chamber, and whereby the buoyancy of the gas will rotate the rotor and actuate said agitating means, said hopper control valve and pressure-responsive means being assembled as a unit independently of the generator and having means for detachably supporting it on the generator casing.

6. In a generator of the class described, a casing having water therein, a wall member within the casing and spaced from the casing wall and having an open end sealed by the water in the generator, said inner wall member defining a gas generating chamber and cooperating with a wall of the casing to provide a gas storage chamber, a carbide hopper having a discharge opening communicating with the gas generating chamber, a carbide feeding mechanism including a rotor, a duct in the lower portion of the gas generating chamber through which the gas must flow from the generating chamber to the storage chamber, the gas flowing through said duct being received in pockets provided in the periphery of the rotor, whereby the rotor is rotated to operate the carbide feeding mechanism, and a pressure responsive device having an operative connection with the carbide feeding mechanism and exposed to the pressure in the generating chamber, whereby when the gas in the generating chamber reaches a predetermined pressure, said device is rendered operable to interrupt operation of the carbide feeding mechanism.

7. In a generator of the class described, a casing having water therein, wall means in said chamber defining a gas generating chamber and cooperating with the casing wall to provide a gas storage chamber, the bottoms of said chambers being defined by the levels of the water in

the respective chambers, a carbide hopper having a discharge opening communicating with the gas generating chamber, a carbide feeding mechanism including a rotor, a duct in the lower portion of the gas generating chamber through which the gas must flow from the generating chamber to the storage chamber, the gas flowing from said duct being received in pockets provided in the periphery of the rotor, whereby the rotor is driven by the differential in pressure of the gas 10

5 in the generating and storage chambers, and a pressure responsive device having an operative connection with the carbide feeding mechanism and exposed to the pressure in the generating chamber, whereby when the gas in the generating chamber reaches a predetermined pressure, said device is operated to render the carbide feeding mechanism inoperative.

ELMER H. SMITH.
